UNITED STATES PATENT OFFICE.

JOSEPH MADER, OF MINNEAPOLIS, MINNESOTA, ASSIGNOR, BY MESNE ASSIGNMENTS, TO NEW BEEMAN TRACTOR COMPANY, OF MINNEAPOLIS, MINNESOTA, A CORPORATION OF MINNESOTA.

TRACTION-MACHINE HITCH FOR SEEDERS.

Application filed January 8, 1920. Serial No. 350,103.

The object of my invention is to provide a means for attaching or connecting a group of seeders to the rear portion of a traction machine of the type that is guided by 5 a walking operator. A further object is to provide a machine of this type of such construction that the seeding devices can perform their functions equally well on smooth or uneven ground. 10 A further and particular object is to provide such a hitch or connection between the frame of the seeder and the traction machine that oscillation of the traction machine is permitted without changing the position of 15 the seeder.

Other objects of the invention will appear from the following detailed description.

The invention consists generally in various constructions and combinations, all as hereinafter described and particularly pointed out in the claims.

In the accompanying drawings forming part of this specification,

Figure 1 is a plan view, partially in section showing the relative arrangement of the traction machine and seeder and the hitch or connection between them,

Figure 2 is a longitudinal sectional view, substantially on the line 2-2 of Figure 1,

Figure 3 is a sectional view on the line 3-3 of Figure 2,

Figure 4 is a sectional view on the line 4-4 of Figure 2.

In the drawing, 2 represents the frame of the traction machine, having the usual supporting wheels 3 and 4 is a bracket mounted on the frame 2 and supporting the steering or handle bars 5 by means of which the machine is guided. An arm 6 is mounted on the bracket 4 and a rod 7 is connected with a casting 8 in which the steering posts are mounted and slideable. The arm 6 is provided with a compression spring 9 which normally holds the steering posts in their raised position. A latch mechanism 10 is provided locking the posts when raised. This above described part of the machine is only incidental to this case.

The bracket 4 is provided with a stud 11 preferably cast therein and projecting rearwardly under the steering posts and a yoke 12 is mounted to rock on said stud and is seated at one end against the bracket 4 and

is prevented from being pulled off the stud by suitable means, such as a cotter pin 13. This yoke has vertical elongated slots 14 therein in which the shanks of suitable ground-working tools may be inserted and on each side the yoke is provided with projecting arms 15 carrying clamps 16 in which a transversely arranged draft bar 17 is mounted. These clamps 16 are secured on the draft bar by suitable means, such as set screws 18. The ends of the draft bar project laterally on each side of the traction machine and the ends are provided with clamps 19 secured by set screws 20 and rods 21 have vertical pivots on said clamps and are provided with 60 caster wheels 22. Between these caster wheels the implement frame of the seeder 70 proper is arranged and I will now describe it in detail.

I prefer to make this implement frame of angle bar metal on account of its strength and rigidity in proportion to its weight, and the forward portion consists of a head bar 23 and the rear portion, of a rail 39, with intermediate cooperating parts hereinafter described in detail. A draft rod 24 is connected at its rear end to the bar 23 and is provided with braces 25. The forward end of the draft rod extends beneath the traction machine to a position substantially concentric with the vertical axis of the machine or at a point directly beneath the axle of the 85 supporting wheels. A socket 26 is provided in the forward end of this draft rod 24 to receive the downwardly turned end 27 of a rod 28, the rear end of which is inserted into a socket 29 in a casting 30 that is mounted 90 on the draft bar 17 and secured thereon by suitable means, such as a clamping bolt 31. A set screw 32 secures the end of the rod 28 in its socket so that forward movement of the traction machine transmits power 95 through the rod 28 to the draft rod 24 and to the frame of the seeder to which the draft rod is attached.

I have shown a row of three seeders mounted in the frame but do not, of course, confine myself to this number, as a greater or less number may be used, as preferred. The seeder is a type which I prefer to purchase in the open market and as its mechanism is well known, and in general use, I 105 will merely refer to the different parts with-

out attempting to describe its construction or operation in detail. For convenience of description, I will designate the seeder in the center as A and those on each side as B.

5 Each of these seeders has furrow discs or wheels 33 and the rear hollow-faced wheels 34 and seed containers 35. The middle seeder has rails 36 and 37 pivoted at 38 to the head rail 23 and the rail 39 parallel with the 10 rail 23 and in the rear thereof is rigidly connected with the bars 36 and 37 by suitable braces 40. This construction provides for a rigid support of the middle seeder on the frame. Each seeder has, of course, the usual 15 boot or shoe 41 through which the seed is deposited in the furrows under the machine. The seeders B are provided with similar bars 36 and 37 which I will designate by the same reference numeral by the addition 20 of the exponents "a" and "b", and they are arranged in substantially the same relation with respect to the frame of the seeder except that the bars 36^a and 37^a and 36^b and 37^b are rigidly secured at their forward ends 25 to the head bar 23. The frames of the seeders proper are all pivoted in a corresponding manner at 42 and are free to oscillate on their pivots and to prevent the wheels 34 from dragging on the ground when the 30 seeder frames are raised, as will be herein-after described, I prefer to provide the bars 37, 37^a, and 37^b with inwardly turned end portions 43 in position to engage arms 44 mounted on the frames of the seeders for 35 the purpose of raising the rear portion of the seeders and the wheels 34 out of contact with the soil, as when the machine is being turned or at any other time when the operator does not desire the seeder wheels 40 to contact with the ground. The frame of the seeder A has straps 45 rigidly connecting it with the bar 39 and to these straps the braces 40 are attached, as shown in Figure 3.

Rods 46 have forked ends pivotally connected at 47 with the bars 36^a and 37^a and 45 36^b and 37^b and the upper ends of these rods are slideable in sockets in the bar 39. Collars 48 and 49 are mounted on these rods 46 above and below the bar 39 and suitable 50 compression springs 50 are mounted on these rods between the collars 49 and the bar 39 to yieldingly resist upward movement of the seeder frames with which they are connected but allowing them to rise and fall 55 with the inequalities of the ground over which the machine may be moving. The adjustment of the collars 48 enables the operator to set the seeder frames at any desired elevation. Figure 3 plainly illustrates 60 this construction, the middle seeder being rigid while those on each side are free to slide vertically in the rear rail of the seeder frame and accommodate themselves to the surface of the ground.

65 The steering bar 5 extends backwardly over

the seeder frame and lifting straps 51 are provided connecting the posts with ears 52 on the bar 39. These lifting straps have adjustable collars 53 to allow the distance between the rods and the seeder frame to be varied, as desired.

I claim as my invention:

1. The combination, with a traction machine frame having supporting traction means, of a ground-working implement frame, a draft bar connected with said traction machine frame, a rod projecting forwardly from said draft bar, draft means mounted on said implement frame and loosely connected with the forwardly projecting end of said rod beneath the axis and substantially in vertical alignment with the middle point between the wheels of said traction machine, and means for guiding said implement frame.

2. The combination, with a traction machine frame having a draft bar provided with a forwardly projecting rod, of an implement frame in the rear of said draft bar and having a draft member projecting forwardly beneath said traction machine and having a loose connection with the forwardly projecting rod of said draft bar beneath the axis, and substantially in vertical alignment with a point midway between the wheels of said traction machine, and means for guiding said implement frame.

3. The combination, with a traction machine having a draft bar supported at both ends on wheels and a rod mounted thereon and projecting forwardly and downwardly to a point beneath said traction machine, of an implement frame in the rear of said draft bar and a draft member mounted on said implement frame and having a pivotal connection with said rod substantially in alignment with a vertical line midway between the wheels of said traction machine.

4. The combination, with a traction machine and a draft bar with wheels at either end thereof and pivotally connected with the traction machine and a rod mounted on said draft bar and projecting forwardly and downwardly therefrom and having a bent end portion, of an implement frame in the rear of said draft bar, a draft member mounted on said implement frame and projecting forwardly beneath said rod and having a socket to loosely receive the bent end of said rod, and handles for guiding said traction machine.

5. The combination, with a traction machine, of an implement frame having a draft connection with said traction machine, including a draft bar supported at either end by a wheel and connected to the traction machine, said implement frame including auxiliary frames, ground working tools pivoted in said auxiliary frames and having front and rear wheels, means for lifting said im-

plement frame, and for simultaneously raising the rear wheels of said ground working tools.

6. The combination, with a traction machine, of an implement frame having a draft connection with said traction machine, including a draft bar supported at either end by a wheel and connected to the traction machine, said implement frame including auxiliary frames, ground working tools pivoted in said auxiliary frames, means for lifting said implement frame and arms extending from said auxiliary frames and positioned to lift the rear portions of said ground working tools when said lifting means and said implement frame are raised.

7. The combination with a traction machine of an implement frame pivotally connected therewith to tilt sidewise, said implement frame including auxiliary frames with ground working tools pivoted in said auxiliary frames and having rear supporting wheels, arms extending from said tool frames, said tool frames having also extensions positioned to engage said arms and lift said tools when said implement frame is lifted, and means connected with said traction machine for lifting said implement frame.

30 8. The combination, with a traction machine, of an implement frame connected therewith and including auxiliary frames, soil treating tools mounted in said auxiliary frames, said implement frame also including a cross bar above said tools, one of said soil treating tools having a rigid connection with said cross bar and others of said tools having freedom of movement with respect to said cross bar to allow said tools 40 to rise and fall with the inequalities of the ground.

9. The combination, with a traction machine, of an implement frame connected therewith and including a head bar, a rear cross bar, and auxiliary frames mounted on said head bar, soil treating tools pivotally supported in said auxiliary frames, the middle auxiliary frame being secured to said rear cross bar, rods mounted on the auxiliary frames on each side of said middle frame and slidable in said rear bar, springs mounted on said rods for yieldingly resisting downward movement thereof, and allowing said tools to adjust themselves to inequalities of the ground, and lifting handles for said implement frame.

10. The combination, with a traction machine, of a yoke mounted for rotary movement thereon, a draft bar carried by said yoke and having caster wheels at the ends thereof, an implement frame connected with said draft bar between said caster wheels,

said implement frame including auxiliary frames, one of said auxiliary frames being rigidly mounted therein and others having 65 freedom of vertical movement, implements mounted in said auxiliary frames, and guiding handles for said implement frame.

11. The combination, with a traction machine, a draft bar supported at either end 70 by a wheel and connected to said machine and having a forwardly and downwardly projecting draft rod, of an implement frame between said wheels and a draft member connected with said implement frame and having its forward end loosely connected with the forward portion of said draft rod.

12. The combination, with a traction machine having a draft bar supported at either end by a wheel and connected to said machine, of an implement frame, draft means connecting said implement frame between said wheels with said draft bar for freedom of relative movement, the point of connection between said draft bar and said implement frame being beneath the axis and substantially in vertical alignment with a point midway between the wheels of said traction machine.

13. The combination, with a traction machine, of an implement frame having a draft connection with said traction machine including a traction bar supported at either end by a wheel, said bar having a pivotal connection with said frame, ground working tools having front and rear wheels and pivotally supported between said wheels in said frame, and means for lifting said implement frame and ground working tools to clear the ground.

14. The combination, with a traction machine, of an implement frame connected therewith, cultivator tool frames mounted in said frame, the middle one of said cultivator tool frames having a rigid connection 105 with said frame and others of said cultivator tool frames having freedom of movement with respect to said frame to allow said tools to rise and fall with the inequalities of the ground.

15. The combination, with a traction machine, of an implement frame connected therewith and provided with a cross member, cultivator tool frames mounted in said frame and connected with said cross member, the middle one of said cultivator tool frames having a rigid connection with said member and others of said cultivator tool frames having freedom of movement to rise and fall 115 with respect to said cross member, for the purpose specified.

In witness whereof, I have hereunto set my hand this 24th day of December, 1919.

JOSEPH MADER.
